UNITED STATES PATENT OFFICE.

THOMAS DUNCAN, OF CHICAGO, ILLINOIS, ASSIGNOR TO DUNCAN ELECTRIC MANUFACTURING COMPANY, OF LA FAYETTE, INDIANA.

ELECTRIC METER.

No. 833,205.

Specification of Letters Patent.

Patented Oct. 16, 1906.

Application filed July 11, 1901. Renewed January 7, 1905. Serial No. 239,967.

To all whom it may concern:

Be it known that I, THOMAS DUNCAN, a citizen of the United States, residing at Chicago, in the county of Cook and State of Illinois, have invented a certain new and useful Improvement in Electric Meters, of which the following is a full, clear, concise, and exact description; reference being had to the accompanying drawings, forming a part of this specification.

My invention relates to electric meters, and has for its objects, first, the construction of a meter which may be readily adjusted for accurate operation upon a circuit of any pressure; second, the provision of means whereby the meter may be adapted to circuits of different frequencies; third, the provision of means for compensating for the diminution of the strength of the drag or damping magnet without altering its position with relation to the disk.

To accomplish the first object of my invention, I provide a portion of magnetic material that is directly associated with the shunt or pressure winding of the meter and which immediately coöperates with this winding to produce a starting torque commensurate with the strength of the pressure-field.

I am aware that portions of magnetic material have been associated inductively with armature-disks for the purpose of overcoming friction; but this torque is furnished by the reaction between the eddy-currents in the armature-disk and the portion of magnetic material. My invention in this respect comprises an element of magnetic material in direct coöperation with the pressure-field winding, whereby a torque is produced that compensates for the different strengths due to the pressure-winding.

Meters as heretofore constructed were adapted for given electromotive forces, and when the meters were to be used in circuits of widely-differing pressures they had to be specially constructed—that is, no standard meter could be adapted to circuits of widely-differing pressures.

By means of my invention I am enabled to construct a standard meter and by properly adjusting the coöperative relation between the pressure field-winding and the magnetic torque-adjusting element am able to adapt the meter to circuits of various electromotive forces. In practicing this feature of the in-

vention the magnetizable element is preferably rotatably mounted and is provided with an index to register with a scale, upon which scale are indicated the various voltages, the index carried by the magnetizable element registering with the scale-mark corresponding with the voltage of the system.

To adapt the standard meter to circuits of different frequencies, I prefer to provide the main pressure-winding with an auxiliary winding that serves to modify the phase of the magnetism due to the pressure-winding to bring the same into the desired phase relation with the pressure of the system. I include in circuit with the main pressure field-winding an adjustable impedance-winding and include in circuit with the auxiliary pressure-winding an adjustable resistance, switches with suitably-marked contact-points being provided for cutting out windings of the adjustable impedance-coil and cutting in the resistance when the frequency is increased, the reverse operations being effected when the frequency is decreased.

To accomplish the third object of my invention, I employ a damping-magnet whose poles are brought close together and between or across which is placed a body of magnetizable material, which by an adjustment of its proximity to the poles of the said magnet determines the amount of flux passing between the poles, whereby the quantity of flux flowing through the damping-disk (which is also preferably the armature of the meter where the invention is applied to alternating-current meters) is determined. The damping-magnet is preferably located over the armature or damping-disk, while a body of magnetizable material, preferably soft iron, is located beneath the armature. This body of magnetizable material is preferably adjustable longitudinally of the axis of rotation of the armature or disk, being preferably movably secured upon the damping-magnet. The flux flowing through the disk may also be adjusted by the movement of this soft-iron body.

By providing a meter that is thus adjustable in the respects above specified the meters may be constructed in large quantities of uniform pattern and size and readily adapted to the various service conditions obtaining in commercial practice, so that a variety of meters need not be carried in stock to suit various working circuits.

I will explain my invention more fully by reference to the accompanying drawings, in which—

Figure 1 illustrates a meter constructed in accordance with my invention, a system of alternating-current distribution being illustrated in combination therewith. Fig. 2 is a detail view showing one of the adjustments for the pressure-field modifier. Fig. 3 is a side view of portions of the apparatus illustrated in Fig. 1. Fig. 4 is a diagrammatic view illustrating the means for adjusting the meter for different frequencies. Fig. 5 is a vector diagram illustrating the phase relations between currents and pressures in the windings.

Like parts are indicated by similar characters of reference throughout the different figures.

I have shown my invention in the embodiment of an alternating-current wattmeter; but there are features of the invention that may be employed in connection with direct-current systems; and I do not, therefore, desire to be limited to the precise application of the invention.

I have illustrated in Figs. 1 and 4 an alternating-current generator 1, supplying current over the transmission-mains 2 2 to transmitting devices 3. The meter is provided with an armature 4, that may also constitute the damping-disk of the meter, although I do not wish to be limited to a construction wherein the damping-disk and armature are in one part. The current-winding 5 is included in series with one of the mains 2. The main pressure-winding 6 is included in shunt of the mains and includes in circuit therewith an adjustable impedance-winding 7, connections being taken from different parts of this winding to the contact-buttons 8 8, corresponding to different commercial frequencies, as illustrated in Fig. 4, or to contact-buttons 9 9, Fig. 1, corresponding to the frequencies of one hundred and forty and sixty periods, that usually obtain in commercial practice. Resistance-buttons 10 10, as illustrated in Fig. 4, or 11 11, as illustrated in Fig. 1, may be provided for adjusting the amount of resistance included in circuit with the auxiliary pressure-winding 12, that is provided for the purpose of modifying the phase of the pressure-field. Switches are associated with the frequency and resistance buttons, which in Fig. 4 are illustrated as separate switches 13 13 and in Fig. 1 are formed in a centrally pivoted switch-bar 13.

The meter may be readily adjusted for frequencies of sixty, one hundred, and one hundred and forty periods. When the meter is to be adjusted, for example, to the highest frequency, only the upper portion of impedance-winding 7 should be included in circuit, while the greatest amount of extraneous resistance should be included in circuit

with the auxiliary pressure-winding. The pressure-windings may be mounted upon a U-shaped core 14, while the current-winding may be supported by a U-shaped body of magnetic material 15, the armature being interposed between the current and pressure windings.

In adjusting or testing the meter it is preferable to commence with the highest pressure to which it may be operated in practice, so that the pressure-coils may be properly adjusted to prevent undue heating when operating continuously at the highest pressure for which the meter is designed. Supposing the meter is to be calibrated for three frequencies—one hundred and forty, one hundred, and sixty periods per second—we will take the lowest frequency first. Since this frequency will give the lowest inductance, all the turns of the impedance-winding should be included in circuit with the pressure-coils 6. This condition is obtained with the connections shown in Fig. 4, where the switch-arm 13 is in contact with the right-hand button 8.

It is well understood by those skilled in the art that to enable a meter to accurately measure inductive loads the magnetism of the shunt or pressure core 14 must be in quadrature with the line electromotive force; but it is impracticable to lag the current to the extent of ninety degrees, as required, by means of the impedance-coil 7 alone on account of its high resistance. Therefore to obtain this required lag of ninety degrees the secondary circuit-coils 12 are wound upon the core 14 in inductive relation to the pressure-coil 6, and the magnetism resulting from the current through the secondary coils 12 is combined with the magnetism resulting from the current in the coils 6 to give the desired lag of ninety degrees. To further illustrate this, let the line *a b* in Fig. 5 represent the current through the shunt-field 6 as lagged by the impedance-coil 7, while *a c* is the impressed electromotive force. Then current through the coils 12 will be represented by the component line *a d*, the resultant of *a b* and *a d* being *a e*, which is in quadrature with the impressed electromotive force represented by *a c*.

Now if the meter is to be used in conjunction with a system employing a higher frequency—say one hundred cycles per second—then arm 13 should be placed upon the center button 8, which cuts out the lower part of the impedance-coil 7. This is done for the purpose of keeping the current through the pressure-coils 6 approximately the same on different frequencies, and since the inductance will be higher on one hundred cycles than on sixty cycles the portion of the impedance already referred to is cut out, so as to permit approximately the same current to traverse it. To illustrate this in a vector

diagram, this current through the pressure-coil 6 may be represented by the line *a f*, and the component *a g* due to the secondary coils 12 gives the same resultant *a e* as in the case 5 of a frequency of sixty cycles. In this change the arm 13 to the right is connected to the center button 10, whereby additional resistance is included in circuit. This increase in resistance brings down the magnitude 10 of the component *a d* on sixty cycles to *a g* on one hundred cycles.

To adjust the meter for one hundred and forty cycles, the arms 13 and 13 are put upon the left-hand buttons 8 and 10, respectively. 15 This cuts out the two lower portions of the impedance-coil 7, while all of the resistance in series with the coil 12 is thereby included in circuit. This being the highest frequency for which the meter is calibrated, only the 20 upper portion of the impedance-coil 7 is used on account of the increased inductance of the pressure-coils, and since the resistance of this portion is less than when the lower frequencies were used with the other portions in 25 circuit also the lag of the current will be greater, as shown by the line *a h*, and by putting all of the resistance in circuit with the coils 12 the magnitude of the component current in 12 is decreased, as shown by the 30 line *a i*. Thus the same resultant *a e* is obtained.

The retarding-magnet 16 is preferably made in the rectilinear shape shown and has between its poles a body of non-magnetic material 17, composed, preferably, of brass, which separates the poles. The poles of the 35 damping-magnet are drawn into tight engagement with this body of non-magnetic material by tightening the screws 18, that 40 pass through riders 19, movable upon the sides of the permanent magnet and engaging the body of magnetic material 20, composed, preferably, of soft iron. The portion or bar 20 of magnetizable material is adjustable 45 independently of the current-winding and the core portion 15, so that the damping effect upon the armature may be adjusted independently of the windings of the meter, the armature being interposed between the poles 50 of the permanent magnet and the body of magnetizable material 20. The body of non-magnetic metal 17 serves as a support for a portion of magnetic metal, preferably in the form of a screw 21, of soft iron. The 55 keeper 20 serves to draw the magnetic flux from the permanent magnet through the disk to complete the circuit for a portion of the lines of force through this keeper rather than directly between the poles of the magnet. 60

When the meter is calibrated, the iron screw 21 is screwed down, as shown, and at some future time, if the drag upon the damping-disk should become weakened, the screw 65 is unscrewed a sufficient amount to increase

the magnetic reluctance between the poles of the permanent magnet, thereby to force the requisite amount of magnetic flux through the disk. The adjustment may be further compensated for by a movement of the keeper 20.

To adapt meters of a given type to systems having widely-differing pressures, I employ an adjusting-body of magnetizable material 22, that compensates for the variation 75 in strength of the pressure-field, this body of magnetizable material being preferably in the form of a flat strip of iron bent at its ends in a plane at right angles to the central portion, which central portion is rotatably secured upon a pin 23 centrally between the pressure-poles, some of the leaves of the magnetic body 15 being removed for the insertion of the corrective element 22. A bracket 24 may also be mounted upon the 80 portion 15, this bracket being preferably provided with adjusting-screws 24', by which the rotary adjustment of the member 22 may be readily effected and secured. The lower portion of the member 22 is in the form of an 85 index that registers with scale-marks 25, indicating the various voltages. When the magnetic member 22 is midway between the pressure-poles, it will have no influence in causing the disk to move in either direction; 90 but as this member 22 is moved toward the left-hand pole, for example, the disk will move, say, clockwise or in the proper direction, and if moved toward the right-hand pole the disk will move in a counterclockwise 95 direction or backward.

If the meter is to register for a fifty-volt circuit, the strength of the pressure-poles will not be as great as when the pressure-winding is subject to a higher pressure. 105 Hence the iron part 22 will be moved to the index-line corresponding to fifty volts. This brings the iron portion 22 to a position in relation with the left-hand pressure-pole so that the tendency toward motion imparted 110 to the disk is sufficient to overcome the friction of the bearings and registering train and at the same time give accurate readings on the low voltage with small loads. This same meter if placed upon a hundred-volt 115 circuit will have to be only modified in its adjustment by having the magnetic body 22 moved until it registers with the scale-mark corresponding to one hundred, which may be accomplished by unscrewing and screwing 120 the screws 24'. This brings the part 22 farther away from the left-hand pole, which is necessary on account of the increased strength of the pressure-field. If the meter is used to register the energy on, say, a two-hundred- 125 volt circuit, the iron part 22 is moved to a position almost midway between the pressure-poles by having the same register with the corresponding volt scale-mark. In this manner the meter is adapted for use on any 130

number of pressure-circuits desired, and the readings are direct without having to use constants or multipliers.

While I have herein shown and particularly described the preferred embodiment of my invention, it is obvious that changes may readily be made without departing from the spirit thereof, and I do not, therefore, wish to be limited to the precise disclosure herein set forth; but,

Having thus described my invention, I claim as new and desire to secure by Letters Patent—

1. The combination with a meter provided with a damping-disk, of a permanent magnet within whose field the damping-disk is arranged, and a body of magnetizable material adjustably secured in position between the poles of the permanent magnet and to be drawn in and out to vary the amount of the same interposed between the poles to govern the magnetic reluctance between the poles of the permanent magnet, substantially as described.

2. The combination with a meter provided with a damping-disk, of a permanent magnet within whose field the damping-disk is arranged, a body of magnetizable material adjustably secured in position between the poles of the permanent magnet and to be drawn in and out to vary the amount of the same interposed between the poles to govern the magnetic reluctance between the poles of the permanent magnet, and a body of magnetic material upon the other side of the damping-disk, substantially as described.

3. The combination with a meter provided with a damping-disk, of a permanent magnet within whose field the damping-disk is arranged, a body of magnetizable material adjustably secured in position between the poles of the permanent magnet and to be drawn in and out to vary the amount of the same interposed between the poles to govern the magnetic reluctance between the poles of the permanent magnet, and a body of soft iron upon the other side of the damping-disk, substantially as described.

4. The combination with a meter provided with a damping-disk, of a permanent magnet within whose field the damping-disk is arranged, a body of magnetizable material adjustably secured in position between the poles of the permanent magnet and to be drawn in and out to vary the amount of the same interposed between the poles to govern the magnetic reluctance between the poles of the permanent magnet, a body of magnetic material upon the other side of the damping-

disk, and means whereby the latter body of magnetizable material may be adjusted from and toward the damping-disk, substantially as described.

5. The combination with a meter provided with a damping-disk, of a permanent magnet within whose field the damping-disk is arranged, a body of magnetizable material adjustably secured in position between the poles of the permanent magnet and to be drawn in and out to vary the amount of the same interposed between the poles to govern the magnetic reluctance between the poles of the permanent magnet, a body of soft iron upon the other side of the damping-disk, and means whereby the latter body of soft iron may be adjusted from and toward the damping-disk, substantially as described.

6. The combination with a meter provided with a damping-disk, of a permanent magnet within whose field the damping-disk is arranged, a body of non-magnetic material interposed and secured in position between the poles of the permanent magnet, and an iron screw secured within this body of non-magnetic material, the screw being interposed between the poles of the permanent magnet and serving to adjust the magnetic reluctance between the same, substantially as described.

7. The combination with a meter provided with a damping-disk, of a damping-magnet, and a body of magnetizable material located opposite the poles of the damping-magnet, the disk being interposed between the pole portions of the damping-magnet and the special body of magnetizable material, the said body of magnetizable material being adjustably secured upon the magnet, substantially as described.

8. In an alternating-current wattmeter, the combination with the current and pressure windings thereof, of an auxiliary pressure-winding for modifying the phase due to the main pressure-winding, an impedance-winding in circuit with the main pressure-winding, a resistance in circuit with the auxiliary pressure-winding, and switches for adjusting the amount of impedance-winding and resistance, whereby the meter may be adapted for circuits conveying current at different frequencies, substantially as described.

In witness whereof I hereunto subscribe my name this 23d day of May, A. D. 1901.

THOMAS DUNCAN.
